UNITED STATES PATENT OFFICE.

RUSSELL T. MANNING, OF MINNEAPOLIS, MINNESOTA.

DESIGN FOR A MATCH HOLDER.

Application filed February 4, 1927. Serial No. 20,616. Term of patent 7 years.

To all whom it may concern:

Be it known that I, RUSSELL T. MANNING, a citizen of the United States, residing at Minneapolis, in the county of Hennepin and State of Minnesota, have invented a new, original, and ornamental Design for Match Holder, of which the following is a specification, reference being had to the accompanying drawing, forming part thereof.

The single view of the drawing is a perspective of a match holder, showing my new design.

I claim:

The ornamental design for a match holder, as shown.

RUSSELL T. MANNING.
